UNITED STATES PATENT OFFICE.

ARTHUR F. C. TOUSSAINT, OF NEW YORK, N. Y.; PHILIP TOUSSAINT ADMINISTRATOR
OF SAID ARTHUR F. C. TOUSSAINT, DECEASED.

SYSTEM FOR AUTOMATICALLY STOPPING RAILWAY-TRAINS.

1,317,405.

Specification of Letters Patent. Patented Sept. 30, 1919.

Application filed December 30, 1915. Serial No. 69,367.

To all whom it may concern:

Be it known that I, ARTHUR F. C. TOUSSAINT, a citizen of the United States, and resident of New York, in the county of 5 New York and State of New York, have invented new and useful Improvements in Systems for Automatically Stopping Railway-Trains, of which the following is a specification.

10 My invention relates to automatic control of traffic moving on a railway for its protection against danger to person and property, one object being to provide in connection with any known or usual signal system 15 and rolling stock, automatic means operating in emergencies likely to effect safety, and independently of the persons controlling movement of a train and, if desired, independently of the persons controlling the 20 usual signals, to stop a train before it approaches or is approached by any condition dangerous to its progress.

Other objects are to provide an automatic train stop which can be employed in addition to and without interference with automatic electric block signal systems in present use, as well as to provide for the protection of trains without decreasing the rate of travel, or the headway interval between 25 trains; and to provide for operation on the normal danger system, so that failures of apparatus secure stoppage. Other objects are to permit the controlled operation of trains when the conditions are dangerous 30 or the apparatus defective, after due actuation or warning to the trainmen.

For the above and other objects my invention may include certain installations on the permanent way and on the rolling-stock, 40 which I have provided in one preferred form in such a manner as to avoid mechanical parts on the roadbed open to danger of breakage or freezing, and so as to secure operation of the devices when the signals 45 normally calling for stoppage or caution are broken, frozen or set falsely to indicate a clear track when there are conditions warranting a signal for danger or caution.

A further object of my invention is to 50 provide an electrically operated system for the general purposes above indicated which shall be inexpensive to install and effective in operation.

In the prior art, so far as I am aware,

reliance for automatic stoppage has been 55 either upon mechanical devices interfering with the train, or electrical devices along the permanent way relied upon to actuate parts carried by the moving train when stoppage is to be secured. One feature of 60 my invention relates to the provision instead on the moving train of means for detecting, with respect to danger or disordered apparatus, the condition of blocks or sections of the track ahead of the moving train and 65 for then automatically operating the brakes or other stoppage devices when the conditions so detected are adverse, by a source of energy moving with the train, so that no source of energy exterior to the train must 70 be relied upon to operate the train-carried parts. I have shown my invention as an instance of one application only in connection with a railway equipped with an automatic block-signal system operating the signals by changes in electric circuits having 75 as elements insulated sections of track, the moving traffic on the railway being depended upon to bridge electrically rails insulated from each other in each of the insulated sections or blocks and thereby to cause the operation of signals protecting the block represented by the pair of rails in each such insulated track section.

Signals of this type are familiar in the 80 art, and while I shall necessarily show and refer to one specific instance of circuits adapted to such signal purposes primarily for the purpose of illustrating the use made of such a system for my new functions, it 85 will be understood without further statement that my invention is adapted without substantial change to coöperate with and utilize parts of other signal systems electrically or mechanically actuated, in which electrical 90 circuits having sections of track or conductors at or near the track arranged to be affected by the moving traffic are elements of the combination, and with respect to which my new devices are operative without any 95 disturbance of the operation of the signal devices.

Other objects, advantages and features of my invention will be apparent from the following description in connection with the 100 accompanying drawings, in which—

Figure 1 is a diagram of the fixed or track circuits representative of two blocks;

Fig. 2 is a diagram illustrating the electrical and mechanical relations of the parts carried by the moving train;

Fig. 3 is an exterior elevation, and Fig. 5 a vertical cross-section on line 4—4 of Fig. 3 of an electrically actuated air-brake valve;

Fig. 5 is a front elevation of the mechanism shown in Figs. 3 and 4;

Fig. 6 is a front elevation of the pair of 10 wheels of a truck showing insulating means therefor;

Fig. 7 is a side elevation partly in section, and

Fig. 8 a front view of replacer mechanism;

15 Figs. 9 and 10 are respectively front and side elevations of the replacer mechanism as inclosed in use;

Fig. 11 is a view similar to Fig. 6 illustrating a preferred form;

20 Fig. 12 is a view illustrating a speed-measuring circuit-breaker and driving means therefor;

Fig. 13 is a diagram similar to Fig. 1 illustrating the arrangement of circuits at a 25 high speed cross-over;

Fig. 14 is a diagram similar to Fig. 1 illustrating an arrangement of circuits at a crossing of another railroad; and

Fig. 15 is a similar diagram illustrating 30 an addition to the devices illustrated in Fig. 1 for the purpose of causing automatic stoppage at each signal-location as well as at the end of each section.

Referring now to Fig. 1, said figure indicates in diagram the fixed circuits including a part of a signal system adapted to protect automatically traffic moving in the direction of the arrow on the track t , t^2 , said figure showing in addition other circuits coöperating with the train-carried parts of my device.

The track may be divided as usual into parts varying in length from 4000 feet to one mile, each part constituting a block, the 45 end of one part and the beginning of another being furnished with a series of electrically-controlled visible signals, two such signal locations X and X' , the intervening block T^3 , T^4 , and an adjacent block T' , T^2 preceding in the direction of traffic on the track in question, being indicated in the figure. The division into blocks of the track is preferably by a break in the electrical continuity of each rail t' , t^2 at the 50 signal location, as shown by the insertion of insulated joints 2 , 2^a in each rail t' , t^2 at the signal location. At each occurrence of the insulated joints 2 , 2^a , usually relied upon for this purpose, the breaks between 55 the electrically-continuous rails are staggered so that the break in the rail t^2 is at least half a rail length ahead of the break in rail t' .

At points preceding in the direction of

traffic each signal location, X , X' , the blocks 65 may be divided into sections T' , T^2 , and T^3 , T^4 , section ends being shown respectively at x and x' , by insulating joints 4 , 4^a staggered in the same manner as the joints 2 , 2^a , and adapted for the usual signal operating 70 purposes.

Otherwise the track t' and the track t^2 are electrically continuous and of low resistance, being bonded in any known or usual manner. As against differences of potential of 75 low value between the rail t' and the rail t^2 , the construction of the road bed is such as not to short-circuit one rail with respect to the other, the usual construction of road-beds sufficing for this purpose with respect 80 to the batteries b , b' connected across the rails at each signal location and at the following end of each section. Batteries b , b' may each have a potential of about two volts. The rail t' at the end of one block is connected to the rail t^2 at the beginning of another block through the resistance r' for a 85 purpose presently to be mentioned.

At the end first approached by traffic of each section T' , T^2 , T^3 , T^4 , low resistance 90 relays A , which may be signal-operating relays, are bridged across the rails of that section. The signal circuits controlled by the relays A (not shown) may be of any desired form. The batteries b , b' maintain the contact-points of these relays closed, except when the moving traffic shunts one of them out by bridging the rails of its section. This movement of the armatures of the relays A may be relied upon to close or open 100 the controlling or operating circuits for the signals displayed behind the moving train, for instance circuits energized from current leads 10 paralleling the track and supplied at intervals by batteries or other source of 105 energy of relatively high voltage, for instance 10 or 12 volts, as shown at b^2 , b^2' . In some prior signal systems, the leads 10 extend only from a signal location to the end of the preceding section of the block behind, 110 as from X' to x' , but I prefer to make the leads 10 continuous.

For my new purposes, I enable some part of a train moved in the direction of the arrow at the end of each section, preferably 115 the locomotive, to include a section, or a circuit representing a section at a distance ahead of it in circuit with electrical detecting apparatus carried by the train, and I so arrange the signal and other track circuits 120 as to secure one detectable electrical condition in said section or representative circuit in case of clear track and operative apparatus, and another detectable condition in case of obstruction, danger, or inoperative apparatus. Preferably the arrangement is that 125 shown in which an electrical circuit controlled by the conditions in the still distant

section, and normally closed, is opened by the operation of devices controlled by the presence of adverse or dangerous conditions at the distant section of track, said circuit 5 having terminals adapted to be connected with the train-carried circuit at points along the track.

At each signal location X , X' , etc., a relay 15 is connected across the current leads 10 10 through contact points 12 operated by relay A (in addition to its signal operating contacts not shown) so as to energize relay 15 when relay A is energized, to maintain contacts 16, 17 closed except when the respective relays A are deenergized. Contact 16 closes the line 20, 24 between a relay 23, at the section-end next behind a signal location, and the positive side of leads 10. I prefer also to carry the line 20 at signal 20 location X' through a contact 21 broken during movement away from clear of the signal semaphore or lantern, whereby to deenergize line 20, 24 and relay 23 on failure of the signal to reach an intended clear position. 25 Relay 23 is connected to the negative side of leads 10 at 24. Operation of a relay A by traffic moving past a signal location will open contact 16 and deenergize relay 23 at the section-end next behind. Relay 23 is 30 also included in another circuit 24, 44 presently to be mentioned whereby it may be energized independently.

Relay 23 controls a contact 25 in a normally closed loop 26 containing a resistance 35 r^2 connecting the rails t' , t^2 between the staggered locations of the insulated joints 4^a 4 at the section-end x' . This loop at x is representative of the distant block T^3 , T^4 , and is adapted to be examined by the detector circuits of the moving train, the fixed 40 circuits described having for one purpose to determine an open condition of said loop at danger in the distant block or failure of the apparatus thereat.

45 Relay 15 also controls a contact point 17, which may be on the same armature as the contact point 16. Contact 17 closes a connection 27 from the negative side of current leads 10 through a slow-action relay 30 and line 31 extending to the section-ends x , x' . Said line may be opened at x , x' , but is kept normally closed at contacts 32 controlled by relays A. The circuit through connection 27, contact 17, relay 30, line 31, contact 32 50 ends at the positive side of the current leads 10, through the connection 33, at the section-ends behind each of the relays 30 in the traffic direction.

Relay 30 is also connected through a contact 34 controlled by its own armature to the negative side of current leads 10, as shown at 35. Having been energized, a relay 30 can therefore be deenergized only by opening the contact 32 at the section-end behind 55 its location. Having been deenergized, it

can be energized again only by closure of both contacts 32 and 17.

At each signal-location the relay 30 controls a contact 45 closing line 44, 24 containing the relay 23 at a section-end ahead 70 of the relay 30 whenever relay 30 is energized.

Traffic passing section-end x to section T^2 will, with respect to relay 30, open contact 32 and deenergize relay 30, breaking in turn 75 the circuit 44, 45, 24 to relay 23 at x' one full block T^2 , T^3 , ahead of the traffic. Having passed in turn on to section T^3 at location X , contact 17 will open to prevent relay 30 and in consequence the relay 23 next 80 ahead from being actuated upon the reenergizing of relay A at x when the traffic leaves section T^2 . But when the traffic has passed into a section beyond location X' , the relays at x and X can coöperate to close 85 the line 44 at 45, to again energize relay 23 at x' , and close loop 26.

Relay 30 is so adjusted as to delay making its contacts when energized, for instance by suitable adjustment of its electro-magnetic 90 properties, or by any other suitable expedient.

The battery b' is so connected to the sections T' , T^3 , etc. as to deenergize the sections T' , T^3 whenever the relay A of the 95 next section ahead in the direction of traffic is deenergized. One well-known connection for this purpose is shown, comprising a contact 40 controlled by relay A at section x , x' , said contact 40 being in series with 100 battery b' and loop 41 connecting the rails t' , t^2 of sections T' , T^3 . The contact 40 may also be arranged as shown, positively to close the loop 41 when the battery connection is broken. Anything deenergizing a relay A at a section-end will therefore deenergize the next relay A behind at a signal-location, opening the loop 26 at the section-end behind the signal-location in turn. A 105 train at section T^4 will thus hold open loop 110 26 at section-end x , when a train is in section T' but will not affect relay A or battery circuit 41 at section-end x .

The described structures are repeated as shown at each signal-location and the preceding track section. The section-ends x , x' , etc., preferably are at the middle of the blocks T' , T^2 , T^3 , T^4 , but for the purposes of my invention they need no further precede each signal-location X , X' , than will 115 suffice to provide a suitable braking distance prior to the next signal-location.

The arrangement of circuits, relays, and sections of a companion track for traffic moving in the other direction, not shown, 120 may repeat that illustrated in Fig. 1 in the opposite direction. The current leads 10 will usually be common to systems for two or more parallel tracks; and where saving in wiring is of importance, the lines 125 130

20, 31 and 44 may be worked duplex for the separate operation of two respective relays for two tracks by any known system suitable for duplex telegraphy, but I prefer 5 the individual wiring illustrated.

Referring now to Fig. 2, each train causes by its movement the successive operation of the relays A, Fig. 1, with the consequent 10 operation of signals and re-arrangement of circuits controlled by relays 15, 23 and 30 as the train passes on to each section of track. The devices carried by the train also include electrical detector means adapted at 15 the passage of the desired points along the way (for instance at each section-end, as x, x', etc.) to examine the condition of a section being approached, for instance, by including in circuit the loop 26, which may be closed, or which may have been opened 20 by the condition of other traffic, or by failure of insulation, or of current, or of the proper operation of signals, or from other causes affecting the track circuits.

Figs. 2 and 11 illustrate in diagram one 25 convenient detector means for this purpose comprising a pair of wheels C, C', rolling on the track and insulated from each other, and means whereby the electrical condition of the track included between said wheels 30 and a pair of electrically connected wheels D, D', separated from them in the direction of the length of the train, may be determined. The wheels C, C' preferably are the front wheels of the bogie truck, and the 35 wheels D, D' preferably are the drive-wheels of the locomotive, but it will be understood that any pair of wheels separated by a distance less than the distance apart of joints 4, 4^a may be utilized as rolling contacts; and I may provide in some 40 cases contact wheels additional to the train-wheels.

The wheels C, C' are not only insulated from each other but from the frame of the 45 engine; and if there are wheels intervening between or closer to the wheels C, C' than the wheels D, D', such as the rear bogie wheels c, c', such wheels are also insulated from each other and from the frame of 50 their carriage, such as the engine.

Preferred means for insulation are illustrated in Fig. 11, in which wheels C, C' are mounted on separate axles 50 rotating in individual journal boxes 51 rigidly attached to but insulated from a frame member 52 of the forward truck of the locomotive. Strong and effective insulation means may comprise, as shown, vulcanized fiber plates 53 held between the frame member 55 52 and the boxes 51 by heavy bolts 54 in holes in the boxes 51 and the member 52 bored out for bushings 55 of the insulating material. Other hard, tough insulating materials may be substituted for the material 60 mentioned.

Between two insulating plates 53 and fitting the bolts 54 I provide a series of contact plates 56 in electrical contact with the bolts 54.

As illustrated in Fig. 11, the wheels C, C' 70 may be mounted on their axles 50 between the bearing ends of the axles, but in some cases I may employ axles 60, Fig. 6, the wheels C, C' being overhung at the respective outer ends and beyond the outermost journal boxes 51. In either case, sufficient strength and rigidity for use as a member of the forward truck of a locomotive is afforded by the described constructions. 75

In a convenient place, as on the locomotive, a detector battery b³ is provided with current leads 61, one of which, shown as the negative, is connected to the magnet coil of a detector relay 65 by a circuit 62 in 80 which the plates 56 are all connected, as illustrated in diagram in Fig. 2. The other side of the coil of the relay 65 is connected at 63 to one of the journal boxes 51 of wheel C, and is therefore in contact with 85 the rail t'.

When the locomotive is on an electrically continuous section of track, relay 65 is energized from battery b³ through a connection 61, 62, to relay 65, and 63 to wheel C, 90 along track t' to D, to D', along rail t² to C', and thence along the connection 66 from one of the journal boxes 51 of wheel C' to the other current lead 61 of battery b³. Connection 66 is controlled at 67 by one of the 95 contacts held closed when relay 65 is energized, so that a break in the continuity of the described circuit including parts of both rails, unless the break is bridged by a track-circuit, will permanently open the 100 detector circuit at 67. One pole of battery b³ is necessarily grounded to the locomotive frame and the track by the connection shown, and any failure of insulation along connection 62 of a sufficiently low resistance 110 to affect the proper operation of the detector devices will close a shunt, (for instance through one of the plates 56) around relay 65, thereby to include failure of the train insulation among the factors causing 115 relay 65 to break all the contacts controlled thereby.

The relay 65 may be energized by a replacer circuit 68 between said relay and the battery b³ when it is desired to permit replacement of the relay armature in its normal attracted position. Said replacer circuit 68 may be in parallel with a circuit 69 having a contact 70 normally closed by relay 65, and circuits 68, 69 are in series with a 120 circuit 71 containing any desired number of circuit-breaking devices 75, 76 actuated according to conditions intended to be laid upon permitting the train to proceed, instances of which will presently be described. 125 130

Movement of the armature of relay 65 whenever said relay detects a break in the circuit between wheels C, C' or is otherwise deenergized initiates the activity of devices 5 operating to stop the train.

Said stopping devices may comprise any known or usual electrically or mechanically actuated devices capable of stopping a train, but I prefer and have herein disclosed electrically operated means, for applying air-brakes of customary construction. I prefer also to extinguish a normally lighted pilot whenever the relay 65 detects an open circuit in the track or is deenergized by any other 15 cause.

In whatever position on the train the wheels C, C', and relay 65 may be placed, said relay controls contacts 72, 73 in local circuits 77, 78, entering the locomotive cab, 20 from a relatively strong source of energy b⁴ carried by the train such as a storage battery of a relatively high voltage and ampere-hour capacity. Batteries b³ and b⁴ preferably are part of the locomotive equipment, 25 which may include suitable re-charging devices, not shown.

Replacer circuit 68 also enters the cab, in which at convenient places for the engineer, a magnet-valve mechanism 80 controlling the brakes, a pilot light 81, and replacer and register mechanism 82 are mounted.

Circuit 78, which passes through and is normally closed in the replacer mechanism 35 82, includes a solenoid 85, Figs. 2 and 4, normally holding a balanced valve 86 against stress of spring 87 closed to check exhaust of the train-line air through ingress pipe 88 and educt pipe 89, so that opening circuit 40 78 sets the brakes on the train. In the preferred form shown, the casing 80 is constructed so as to inclose effectively against unauthorized opening casting 90, 91 having a central chamber and seats for the rigidly 45 connected valve heads 86 on stem 92, which is rigidly attached to an iron armature 93 free in a brass lining 94 surrounded by solenoid 85, which may if desired be inclosed in a casing 95 and rest on an insulating base 96. Spring 87 is normally overcome by the attraction of the solenoid, the design of the parts 86 being such as to eliminate any considerable resistance to movement of the valve due to air-pressure, as 55 shown. Lamp 81 is conveniently mounted as shown on a flange of the magnet-valve mechanism, from which leads a conduit 97 for the wires of circuits 77, 78. A glass window 98 in casing 80 permits the lamp 60 to be seen.

Another breakable glass window 99 in casing 80 gives access in an emergency to a cock 100 adapted to close train-air pipe 88.

The replacer mechanism 82, Figs. 7 to 65 10, comprises a base 105 having bearings

for a shaft 106 carrying a cylinder 107 surrounded by an insulating sleeve 108, upon which conducting contact-making sectors 109, 110 are fixed in peripheral grooves, as by insulated bolts 111 passing through lugs 112 70 of the sectors.

Sectors 109 and 110 are adapted respectively, in positions 180° apart of shaft 106, to connect a pair of separated contact-forks 113, 113, 114, 114, said shaft being provided 75 with a handle 115, and a ratchet and pawl 116, 117 to prevent turning the shaft backward. Bevel gears 118 connect shaft 106 to a revolution-counting register 119 of any usual construction. A casing 120, secured 80 to base 105 in any manner adapted to prevent unauthorized access, has an opening for shaft 106 and handle 115 and a suitable window 121 permitting the register to be read.

Circuit 78 is normally completed between 85 the forks 114 by sector 110. When sector 109 is in any other position than in contact with said forks, magnet valve 80 is open, and the train can not move.

Replacer circuit 68 is normally broken between forks 113, but can be completed by sector 109 whenever the train is stopped, or by causing stoppage, on turning handle 115 through half a revolution. To start the train, handle 115 must be turned through 95 the remainder of a revolution. Such revolution is registered at the counter 119.

It is desirable on many occasions, as when taking a siding or a slow-speed cross-over, or in an emergency when proceeding at caution into a block in which the automatic devices have gone to danger, or are kept set at danger, to operate the train at a slow speed without any interference by the automatic devices. I have therefore provided as shown 100 in Figs. 2, 11 and 12 for separately energizing the detector relay 65 whenever the train speed is below a fixed minimum. For this purpose the circuit 69, 71 includes a circuit-breaker 75 having an element driven as by 105 belt 124, from an axle, as 50, and adapted to break said circuit 71 at a fixed speed, for instance when the train is running above ten miles per hour. I have not shown the device 75 in detail, any commercial circuit-controlling speedometer adapted to be driven by the train wheels being adapted to my said purpose. 115

I provide for opening the circuit 71 whenever the driving connection to the device 75 120 fails, as by breakage of the belt. One device for this purpose as shown comprises an idler pulley 125 for belt 124 mounted on an arm 127 fast to a shaft 126 of a cylindric circuit-breaking switch 76, and adapted 125 when the belt 124 breaks or runs off to fall, rocking shaft 126 and breaking circuit 71.

My system may be adapted to all the usual track conditions by simple provisions of the track circuits. Referring now to Fig. 130

13 for instance, said figure shows a high-speed cross-over T^{10} for diverting traffic in the direction of the arrows from a track T^7 to a track T^8 . As shown, track T^8 may be divided into sections by the insulated joints 2, 2^a, and as shown a section of the track T^8 , the cross-over T^{10} , and so much of the track T^7 as is illustrated may have the usual signal circuit connections 151, 152, 153, 154, section T^9 having a battery b and relay A as described in connection with Fig. 1.

10 The cross-over T^{10} is broken at three places by staggered insulated joints 5^a, 5^b; 6^a, 6^b; and 7^a, 7^b. At the staggered ends between joints 6^a and 6^b, I provide a loop 150 to connect the rails of cross-over T^{10} . The section T^9 is also provided with the closed loops r' similar to those above described.

15 As will be readily perceived from the diagram, the effect of the loops r' , r'' and 150 is to maintain as between the wheels C, C' moving over the cross-over the electrical continuity of the track T^{10} whether considered as a section with respect to the track T^7 or section T^9 of the track T^8 . Presence of a train at the cross-over will actuate relay A in the same manner as that described for a train on one of the sections shown in Fig. 1.

20 In Fig. 14, a crossing with a transverse railroad I is illustrated, along with the adjacent signal locations X^5 , X^6 for railway T^{11} . The parallelogram P at the intersecting tracks is insulated at one rail of each of the crossing tracks by an insulating joint 8^a and the abutting ends of the sections of the track T^{11} are connected as shown, rail t^2 being looped at 160 to rail t' beyond the crossing railroad, whose rails may be connected in a similar manner at loop 161.

25 40 With respect to the battery b and rolling contacts C, C' there is no break in continuity between the signal locations X^5 , X^6 .

30 The insulated joints mentioned above are relatively narrow in the direction of travel, and it will be understood that the rolling contacts mentioned either bridge the abutting ends of the rails in passing such a joint or are out of contact with the abutting rails for so brief an interval as to fail to actuate any of the devices and circuits controlled by such a contact merely by passage across the insulated joint.

35 45 In Fig. 15 I have illustrated, for addition to the circuit shown at Fig. 1, means to cause the above described automatic stop devices to become operative at the signal-locations X , X' as well as at the section-ends x , x' . For this purpose the loops r' joining the opposite rails of abutting sections are replaced by loops 165 arranged to be broken at contact 166 by relay 170 connected at 171 across the current leads 10, connection 171 being in turn controlled by a contact 172 of the relay 23 at the section-

end next preceding the signal-location in 65 the direction of traffic.

50 In operation, referring now to Figs. 1 and 2, first assuming the block T to be clear and an operative condition for all batteries, circuits and signals, and a train approaching the section-end x in the direction of the arrow, the relays A will then all be energized and the fixed circuits in the condition shown, the contacts 12 being closed. At x the relay 23 is energized and the loop 26 is 75 closed. On the train, the detector circuit containing the parts of tracks t' , t^2 between wheels C, D and C', D' respectively, the relay 65 and battery b^3 , is closed by the rails.

80 At passage over joint 4^a of wheel C', circuit C, D, t' , t^2 , D' C' broke at the joint 4^a in track t^2 , but was replaced by loop 26. At passage over joint 4, said circuit C etc. to C' broke at joint 4, but was replaced by the leads and coil of relay A. When wheels 85 D passed joint 4 the low resistance shunt D, D' deenergized relay A at x and opened contacts 32 and 40, deenergizing track section T' by cutting out or bridging battery b' , or both, and deenergizing relay 30. Relay 30 thus opens contacts 34, 45, the break at the latter contact cutting line 44 to relay 23 at section-end x' , one full block ahead, but not inducing movement of said relay which is still energized by line 20, 24 reaching 90 farther ahead still to signal-location X'. The train is now on section T^2 , with clear signals set at signal-location X.

95 As the train passes location X, loop r' , which may be permanently closed through 100 a resistance preferably greater than that of the adjacent relay A, maintains the locomotive detector circuit closed, and relay A is shunted out by the wheels D, D', opening its contact 12, and deenergizing relay 105 15, thereby opening line 20 to the rear of the train, and through relay 23 at x opening loop 26 at 25, unless there is current on line 44, which as explained above will not be possible if there is a following train on 110 section T'. The open loop 26 is a stop indication for a following train.

115 Relay 15 when deenergized not only opened line 20, but at contact 17 broke circuit 27 to relay 30. This occurred before section T^2 was freed by the bridging train, thereby to avoid first closing contact 32 and thus independently energizing relay 30 and continuing its energization through connection 35, 34. If the moving traffic was a locomotive running light, so as to cause an interval when no bridging wheels were on section T^2 and before relay 15 has acted, relay 30 will still remain deenergized because it is slower in action than relay 15, the possible time interval being very short. The train having passed X, the relay 30 at X and the relay 23 at x remain deenergized.

The relays A and 23 at the section-end α' ahead of the train now on section T^3 remain closed through the rails of section T^4 and line 20 to signal location X' , and the locomotive detector circuit still finds continuity between the end of rail t' of section T^3 and the overlapped end of rail t^2 of section T^4 , as explained in connection with section-end α .

- 10 When the train passes to section T^4 , relay A at α' cuts out battery b' for section T^3 , thus keeping relay A at X , relay 15 at X , and relay 23 at α deenergized. A danger signal will be displayed at X and the 15 loop 26 at α will remain open, to stop following traffic until the train leaves section T^4 . Having left section T^4 , relay A at α' is energized, whereupon relay A at X , relays 15 and 30 at X , and relay 23 at α are 20 energized, and the line is cleared to and inclusive of section T^4 . But an approaching following train, assuming the first train to be stalled at or just beyond signal-location X' , will break the line 44 by means of the 25 relay 30, line 31, contact 32 and relay A at section-end α , so that loop 26 at α' will be opened by failure of current at relay 23 at that point, whether or not the train has cleared section T^4 , or whether the condition 30 occurred after the second train has passed section-end α .

Failure of any of the insulated joints 2, 2^a, 4, 4^a will result in deenergizing a relay A, and setting the signals and causing open-circuit at loop 26 at the section-end preceding. Improper motion of any signal, through contact 21, will be equivalent to deenergizing relay 15 by a train on the next block, and break line 20 to open loop 26 at 40 the preceding section-end. Failure of any track-connected circuit necessarily causes the same result.

Assuming that for some one of the causes mentioned a loop 26 or r' is an open circuit, the detector and other train-carried circuits on a train at speeds above a predetermined slow speed operate as follows:

Relay 65 whenever the circuit between wheels C, C' opens breaks contacts 67, 72, 50 73, 70. Contact 67 opens the lead 61, 66 from battery b^3 , so that a very short break in time permits the relay armature to drop and prevents its restoration.

Contact 72 opens to extinguish lamp 81. 55 Contact 70 opens to break circuit 69, 71 by which relay 65 might again be energized.

Contact 73 breaks the circuit 78 to magnet-valve 80, and applies the brakes.

Every possible connection from battery 60 b^3 to relay 65 is now broken except that through disk 109 of replacer 82, which is open.

Circuit 78 to the valve, without closing which the brakes can not be released, (except by breaking emergency window 99) can

not be closed at 73 without operating the replacer, and can not then be closed unless the train has stopped or is running so slowly as to close circuit 71 at 75. The engineer now turns the replacer handle one-half revolution away from the position shown in Figs. 7 to 9, thus making circuit 68, and restoring current to relay 65 through 71, 68, 62, and closing contact 73 in circuit 78. But circuit 78 is now broken at disk 110, forks 75 114, and handle 115 must be turned through the remainder of the revolution to close valve 80. Register 119 records how many times the engineer has operated his replacer.

The locomotive circuits are now complete, 80 and if the track-condition still is such as would again deenergize relay 65, the train may still be run at a limited speed by intervention of the speed-controlled circuit breaker 75, which maintains the circuit 71, 85 69 closed, when the relay 65 has once been energized to close contact 70, at all speeds under a prescribed minimum, for instance ten miles per hour. Any danger or stop indication may be passed at such low speeds 90 without automatic setting of the brakes, and the locomotive may be run into roundhouses or on to sidings or over other unbonded or imperfectly conducting sections at such speeds without intervention by the engineer. 95 I find this provision useful for enforcing "slow" orders, an open-circuit track section being provided to make the engineer slow down, or be stopped. The circuits of a regular section may be made continuous around 100 such a break, or one of the loops r' may be broken for this purpose. The belt-operated device 76 prevents any restoration of relay 65 when the speed-controlled device 75 is not running. When it is desired to increase 105 the number of points at which a loop is automatically opened between abutting sections to secure stoppage, the arrangement of Fig. 15 is preferred, as above described. Operation of the device will be obvious in 110 view of their analogy to those above.

It will be seen that by the device of enabling a train-carried circuit to include and determine the electrical continuity of a circuit between the abutting ends of certain 115 track-sections that I am enabled to secure the safe operation of a train automatically without any difficult changes in construction or equipment and without interference with the automatic block signals now used. While 120 I have mentioned opening certain circuits or breaking connections or disturbing the electrical continuity of parts, as of the loops 26 or parts of the tracks, it will be understood that such opening, breaking or disturbance 125 of any of the circuits may be relative only, and may comprise a mere increase of resistance; and that the conditions detected by the detector circuit and relay 65 may be normal conductivity and increased resistance re- 130

spectively, it being apparent that the constants of the relay 65, the detector circuit containing it and the source of energy therein may be chosen to cause actuation or release of the relay armature at any desired resistance of the fixed circuits or parts of the track included therein.

While I prefer that the electrically controlled stopping device 80 shall be an air-brake valve as shown and described, the said device may be instead the controller or circuit-changer or transformer switch for electric driving motors; or said valve 80 may be a valve in a pneumatic or other fluid-pressure system for signaling the trainmen instead of or in addition to directly affecting the actuation of the locomotive; or may be the throttle-valve or a controlling device for the throttle-valve of a steam locomotive. It will also be apparent that the circuit 78 may control any desired number of train-stopping devices instead of or in addition to that shown, such as a throttle-valve or controller handle, to be released whenever the brakes are set.

It will now be understood without further description that my device is adapted for certain operation in all the emergencies usually provided against by signals, including its own failure, and that the trains will be stopped at the selected places with a minimum of disturbance, and that they need never be so stopped if the engineer obeys signals, except in case of apparatus failure. While I have shown in illustration of the genus of devices which my invention includes, preferred forms of circuits for giving a stop indication at the section-ends, and preferred forms of devices for detecting such an indication, and for stopping in response thereto, it will be understood that other species not explained in detail herein, within the scope defined by the accompanying claims, may be substituted for the instances selected for illustration of the invention.

From the foregoing it will be apparent that the bridge 26 at a position α is rendered effective to stop a train only when a section of the following block is short circuited and when a train successively enters the two preceding sections, this being due to the fact that the relay 23 controlling the bridge 26 is controlled over conductor 20 from the following block and also over conductor 44 in parallel with conductor 20 from the succeeding sections and to the fact that the relay 23 is deenergized to open the bridge 26 when a train enters the second preceding section and is maintained open by the train passing from the second preceding section to the first preceding section. Thus, referring to Fig. 1, if a train is in section T^5 the relay 15 will be deenergized to open the circuit 20 of relay 23. However, the relay 23 will not be deenergized to open the bridge 26 until the

circuit 44 is opened. The circuit 44 is opened at 45 when a train enters section T^2 inasmuch as the relay A at T^2 opens a circuit of relay 30 controlling contact 45. At this time the bridge 26 at position α' is opened. When the train passes from section T^2 to section T^3 the relay A at T^2 closes, but the relay 30 does not close inasmuch as its circuit 27 is opened at 17 by the train entering section T^3 . Thus the relay 30 is maintained deenergized as the train passes from section T^2 to the section T^3 , thereby maintaining the bridge 26 at position α' open. In the case of a single locomotive or a single car passing from T^2 to T^3 the relay 30 would pull up while the locomotive or car is between points 2 and 2^a in the track if it were not for the fact that the relay 30 is slow acting. Thus the arrangement is such that when there is a condition of danger ahead the bridge 26 is opened when a train enters the second preceding section T^2 and is maintained open to stop the train when the train passes from the second preceding section T^2 to the first preceding section T^3 . A single train passing over the track will not affect the relays 23.

What I claim is:

1. In a system of the character described, the combination of a train-carried detector circuit completed in part through the track, circuit-breaking means for breaking the electrical continuity of predetermined parts of the track, and control means for controlling said circuit-breaking means by the conjoint presence of a danger condition ahead and a train passing from one section to another section in the rear.

2. In a system of the character described, the combination of a train-carried detector circuit including a part of the track between contacts moving with the train, means whereby a break in electrical continuity of said part of the track alters said detector circuit, means for breaking the electrical continuity of predetermined parts of the track, and means for mutually controlling the last aforesaid means from both directions so that the track continuity is conditioned to operate said detector circuit by the conjoint action of a danger condition ahead and the train successively entering to preceding sections.

3. An automatic stop system comprising a train-carried detector circuit including a part of a track circuit, means responsive to an alteration in the electrical condition of said track circuit for stopping the train passing from one section to another section, circuit-closing means for opening and closing the track circuit at a predetermined point, and means responsive conjointly to a condition of danger ahead of said point and to a train in the rear of said point for controlling said circuit-closing means.

4. An automatic electric stop device for

- 5 railways comprising an insulated rail section overlapping another insulated rail section, and detector means carried by a moving vehicle on said railway adapted to detect connection or disconnection between said overlapping rail sections, in combination with means for connecting and disconnecting said rail sections in response to conditions affecting safety at a distant part 10 of the railway.
5. An automatic electric stop device for railways comprising signal operating track circuits, each having an insulated rail section overlapping another insulated rail section 15 of an adjacent track-circuit, and detector means carried by a moving vehicle on said railway adapted to detect connection or disconnection between said overlapping rail sections, in combination with means for 20 connecting and disconnecting said rail sections in response to conditions affecting safety at a distant part of the railway.
6. Means for use on railways adapted to actuate parts carried by a moving vehicle in 25 response to conditions at a section ahead of said vehicle comprising, in combination, a track electrically divided into similar continuous successive sections, a conducting loop adapted to connect one section to an adjacent section; means comprising a conductor along the track, a source of energy and devices worked thereby to open and close said loop; and a circuit controller at each section for altering the continuity of 30 said conductor to a section in the rear.
7. Means for use on railways adapted to actuate parts carried by a moving vehicle in response to conditions on a section ahead of said vehicle comprising in combination 35 a track electrically divided into similar continuous successive sections, a normally closed circuit connecting one section to an adjacent section; means comprising a conductor along the track, a source of energy and devices adapted to open said normally closed circuit, and circuit controllers at each section for altering the continuity of said conductor to a section in the rear, whereby to operate said devices.
8. Means for use on railways, comprising an insulated track divided into sections each comprising equal continuous portions of both sides of the track overlapping each other, and including means adapted to operate signals automatically by contact with a moving train, in combination with a conducting loop normally connecting the overlapping portion of the track-sections, means for opening and closing said loop at the occurrence or absence of conditions causing a danger signal and a detector circuit carried by the train for determining the condition of said loop.
9. Means for use on railways, comprising an insulated track divided into sections each comprising electrically continuous portions of both sides of the track overlapping each other, and including means adapted to operate signals automatically by contact with a moving train, in combination with a conducting loop normally connecting the overlapping portions of the track-sections, means for opening and closing said loop at the occurrence or absence of conditions causing a danger signal, a detector circuit carried by the train for determining the condition of said loop, and means actuated by the indications of said detector circuit for stopping the train.
10. An automatic stop device for railways, having in combination a track divided into track-circuit sections, each track section being electrically continuous and comprising portions of both track rails overlapping each other, a detector circuit and source of energy therein carried by a vehicle moving on the track adapted to determine presence or absence of an electrical connection between the overlapping portions of two or more of said sections, and means on said vehicle adapted to be operated by a source of energy thereon to stop said vehicle controlled by one indication of said detector circuit.
11. In an automatic stop device for railways, a track having insulated rails in each side of the track, electric circuits connecting opposite rails in successive sections, means carried by a vehicle moving on the track adapted to connect the rails together to affect said electric circuits of which the rails are elements, in combination with means on said vehicle to detect presence or absence of an electrical connection between successive sections of said track, and stopping mechanism actuated by said means.
12. An automatic electric stop device for railways, having insulated rails divided into mutually insulated track sections abutting each other, each track section comprising equal continuous portions of both sides of the track overlapping each other, comprising connecting means and detector means moving with a vehicle on said railway adapted respectively to connect rail to rail, and to bridge abutting ends of said track sections, in combination with means for connecting and disconnecting said abutting ends in response to conditions affecting safety at a distant part of the railway being approached by said vehicle, whereby to affect said detector means.
13. Means for use on railways, adapted to actuate parts carried by a moving vehicle in response to conditions on a section ahead of said vehicle, comprising in combination a track electrically divided at signal locations into blocks, said blocks being similarly divided into successive sections, a conducting loop adapted to connect one section to an adjacent section, means for opening and closing

said loop including a conductor extending from one signal location to said loop at section ends to the rear, and means operated by the passage of a vehicle at said signal location for altering the continuity of said conductor.

14. Automatic train-stopping means for use on railways, comprising in combination a track electrically divided into successive sections which are closed charged circuits, relays in each of said circuits adapted to be operated by traffic in each section, a connecting loop adapted to connect one side of one section to the other side of an adjacent section, means comprising a circuit adapted to be opened by two of said relays for opening said loop when there is traffic on both of said sections simultaneously, and means on a train adapted to be operated when, at passage from one section to another, there is an open circuit between said sections of track.

15. An automatic train stop comprising a railway vehicle having a pair of rail-contacts connected together, and a pair of insulated rail-contacts at a distance therefrom, said insulated contacts forming the terminals of a normally closed detector circuit adapted to be opened by a break in the continuity of either or both rails between said insulated and said connected contacts, a track divided into blocks, one side of each block overlapping one side of an adjacent block, and a train-controlled circuit connecting the overlapping sides, whereby the presence of a train in a preceding block will open said circuit and open the detector circuit of a train crossing the overlapping portions of the sides of the track.

40 16. An automatic stopping device for railway vehicles comprising an electrically-operated control device on the vehicle, an operating circuit therefor, and means to alter the continuity of said circuit comprising a detector relay, a source of energy, and a circuit including in series wheels insulated from each other, portions of the rails and wheels adapted to connect the rails, whereby a break in continuity of either rail operates said control device, a track divided into blocks, one side of each block overlapping one side of an adjacent block, and a train-controlled circuit connecting the overlapping sides, whereby the presence of a train in a preceding block will open said circuit and open the detector circuit of a train crossing the overlapping portions of the sides of the track.

60 17. An automatic electric stopping device for railways, comprising a detector circuit having therein in series a source of energy, terminals adapted to include a circuit whose condition is to be detected, and a magnet coil of a relay having contact points adapted to open said circuit when deenergized, as by

a discontinuous circuit between said terminals, in combination with a controller-circuit adapted to be altered when said relay is deenergized, stopping means operated by said controller circuit and manually operated replacer means adapted to close a normally open circuit across said contact points and simultaneously break said controller circuit.

70 18. A railway vehicle having a detector device adapted to include the rails and an electrically connected pair of wheels thereon in a circuit, comprising said wheels, in combination with a truck frame, journal boxes thereon insulated therefrom, and separate aligned axles having wheels thereon held by said boxes for contact with the respective rails.

75 19. In an automatic electric stop system for railways, the combination of a vehicle with a detector circuit arranged to be closed through the track, stop indication means associated with the track, and electro-magnetic means in said circuit adapted to operate in one condition of said indication means to cause stoppage, in combination with means controlled by the speed of the vehicle for independently actuating said electro-magnetic means to prevent stoppage at speeds less than a predetermined speed, the last means having a circuit controlled by the electromagnetic means.

80 100 20. An automatic vehicle stop device having in combination with the vehicle a fluid-pressure brake system, a valve, means tending to open said valve to set the brakes, electro-magnetic means for holding said valve closed, a normally closed circuit and source of energy on said vehicle for energizing said means, automatic means for interrupting said circuit to set the brakes, manually operable interrupting means therefor on said vehicle, and speed-control means for energizing said electromagnetic means to maintain the brakes released.

105 110 21. Automatic train-stop devices having a detector-circuit and circuit-breaking means carried by the train adapted to be actuated by the electrical condition of predetermined parts of a railway, in combination with an electro-magnetic valve controlling stopping means for the train in a local circuit controlled by said circuit-breaking means, and manually operated replacer means adapted to operate said valve-mechanism and said circuit-breaking means in two successive positions thereof, whereby to insure stoppage of the train before restoration of the automatic devices to a condition permitting the train to proceed.

115 120 125 22. An automatic train-stop having in combination train-carried devices comprising a detector-circuit, and a local-circuit-controlling relay for operation thereby, adapted to open its own actuating circuit on the occur-

- rence of one condition affecting said detector-circuit; train-stopping devices actuated by a local circuit controlled by said relay; replacer means adapted to reenergize said relay during an effective position of said train-stopping means only; and speed-controlled means for independently energizing said relay through a local circuit adapted to be broken when said relay opens its actuating circuit, whereby the automatic devices are rendered inoperative at slow train speeds, but, having acted, will permit the train to move only when the train has been stopped and the devices then reset.
23. In an automatic electric train-stop system, in combination with stop-indicating loops at predetermined parts of a railway adapted to be included in a train-carried circuit for effecting stoppage or procedure, means for controlling said loops comprising a track divided into sections; means at a section ahead of said loop for closing a circuit containing electro-magnetic means adapted to alter the continuity of said loop when there is traffic on said section; and means controlling a conductor to a section behind said loop for independently energizing said electro-magnetic means in response to absence of traffic in one or more sections behind.
24. In an automatic electric train-stop system for railways, a track-loop adapted to be opened and closed to effect stoppage or procedure of passing trains, in combination with an electrically actuated opening and closing device therefor, means at a section of track ahead in the direction of traffic for operating said device when there is traffic in said section ahead, and an independent energizing circuit for operating said device controlled by traffic in sections to the rear, and a relay and an operating circuit adapted to be broken in one place by traffic in one section and another place by traffic in another section, said independent circuit being controlled by said relay and operating circuit.
25. Railway protective apparatus comprising a train-carried detector circuit, means for opening and closing said circuit in response to conditions affecting the safety of the train at a distant part of the railway being approached by the train, an electromagnetic device in said circuit, a branch circuit including said electromagnetic device, and an armature switch of the electromagnetic device, and a speed-controlled device in the branch circuit for maintaining the circuit closed while the train is running at low speed.
26. Railway protective apparatus comprising a train-carried detector circuit arranged to be normally closed through a portion of the track, an electromagnet in said circuit, the electromagnet having an armature
- switch arranged in series therewith in said circuit so as to close the circuit when energized, a branch circuit including said electromagnetic device, said electromagnetic device having a second armature switch in the branch circuit, both switches being arranged to be closed when the device is energized, and a speed-controlled device in the branch circuit for maintaining the branch circuit closed while the train is running at low speed.
27. In a railway system comprising a track divided into blocks, the combination of electrical mechanism carried by the train, a controlling circuit associated with one track block, the operation of the train mechanism being dependent upon the continuity of the controlling circuit, circuit-controlling means for controlling the continuity of the controlling circuit, and train-controlled means for controlling the circuit-controlling means, the train-controlled means being so associated with said one block and a preceding block that normally the circuit-controlling means is only conditioned to operate train mechanism when trains are in each of said blocks.
28. In a railway system comprising a track divided into blocks, the combination of electrical mechanism carried by the train, a controlling circuit associated with one track block, the operation of the train mechanism being dependent upon the continuity of the controlling circuit, a first relay for controlling the continuity of the controlling circuit, second and third relays for controlling the first relay, the second relay being associated with said block so that its operation is dependent upon the presence of a train in the block, and the third relay being associated with a preceding block so that its operation is dependent upon the presence of a train in the preceding block, whereby the first relay is only operated to condition the controlling circuit so as to actuate train mechanism when trains are in both of said blocks.
29. In combination with a railway system divided into blocks, the insulating joints between blocks being staggered so that the rails of adjoining blocks overlap, a circuit bridging the overlapping portions of two blocks, means for opening and closing said circuit, train-carried mechanism arranged to be actuated when the train passes from the first to the second block depending upon the continuity of said circuit, a relay associated with each of said blocks so as to be actuated by a train in the block, and means for connecting the relays to the said means so that the means is only operated to change the condition of the said circuit when trains are simultaneously in said blocks respectively.
30. A system of the character described

- comprising a track divided into sections, relays associated with the respective sections, and means for controlling a relay of a section conjointly by a condition of danger in 5 a succeeding section and by a train successively entering two preceding sections.
31. A system of the character described comprising a track divided into sections, relays associated with the respective sections, 10 and means for controlling a relay of a section conjointly by a condition of danger in the next succeeding section and by a train successively entering two preceding sections.
32. A system of the character described 15 comprising a track divided into sections, relays associated with the respective sections, and means for controlling a relay of a section conjointly by a condition of danger in a succeeding section and by a train successively entering the next two preceding sections.
33. A system of the character described 20 comprising a track divided into sections, relays associated with the respective sections, and means for controlling a relay of a section conjointly by a condition of danger in the second succeeding section and by a train successively entering two preceding sections.
34. A system of the character described 25 comprising a track divided into blocks, the blocks being divided into sections, relays associated with the respective sections, and means for operating the relay of a certain section of a block conjointly by the presence 30 of a condition of danger in a succeeding block and by a train successively entering a section of a preceding block and a section of said block.
35. A system of the character described 35 comprising a track divided into blocks, each block being divided into sections, a relay for controlling the electrical condition of a block at the middle of the block, and means for operating said relay, said means being responsive to the conjoint action of a condition 40 of danger in the first section of the succeeding block and to a train successively entering the last section of the preceding block and the first section of said block.
50. 36. A system of the character described comprising a track divided into sections, means at the junctions of sections for controlling train mechanism, train mechanism arranged to be brought into operative rela- 55 tionship with said means at the junctions, and electrical means including a slow-acting relay responsive to conditions in the respective sections for operating said first means, the first means at one junction being conditioned by the electrical means when a train 60 successively enters two preceding sections while a danger condition exists in a succeeding section.
37. A system of the character described comprising a track divided into sections, 65 means at the junctions of sections for controlling train mechanism, train mechanism arranged to be brought into operative relationship with said means at the junctions, and electrical means responsive to conditions 70 in the respective sections for operating said first means, the first means at one junction being rendered effective to operate the train mechanism by the electrical means only when a train successively enters two preceding sections while a danger condition exists in the 75 second succeeding section.
38. A system of the character described comprising a track divided into sections, 80 means at the junctions of sections for controlling train mechanism, train mechanism arranged to be brought into operative relationship with said means at the junctions, and electrical means responsive to conditions 85 in the respective sections for operating said first means, the first means at one junction being rendered effective to operate the train mechanism by the electrical means when only a train successively enters two preceding sections while a danger condition exists 90 in the third succeeding section.
39. A system of the character described comprising a track divided into sections, 95 means at the junctions of sections for controlling train mechanism, train mechanism arranged to be brought into operative relationship with said means at the junctions, and electrical means responsive to conditions 100 in the respective sections for operating said first means, the first means at one junction being rendered effective to operate the train mechanism by the electrical means when only a train successively enters two preceding sections while a danger condition exists 105 in the second or third succeeding section.

Signed by me at New York, N. Y., this 20th day of December, 1915.

ARTHUR F. C. TOUSSAINT.
